UNITED STATES PATENT OFFICE

BRUNO SIMONIDES, OF MANNHEIM, GERMANY

STOCKING DRYING AND SHAPING FORM

Original application filed August 29, 1927, Serial No. 216,062, and in Germany December 30, 1926. Divided and this application filed September 12, 1929. Serial No. 391,997.

This invention relates to a stocking drying and shaping form, designed to be heated internally by means of steam, air or other fluid, and over which the stockings are drawn in order to treat them.

The present application is a division of my application Serial No. 216,062, for ironing, shaping and drying apparatus, filed August 29, 1927.

10 It is important in practice that the heat of the heating fluid be distributed uniformly to the walls of the shaping and drying form. The fabric of the stockings must be protected from contact with the fluid and also from excessive heating. The fluid must be highly heated in order to increase the economy of the drying process.

It is known to lead the heating fluid into one-half of the interior of the form upwardly 20 and into the other half downwardly. With this method of leading in and out the heating fluid, the first half of the form becomes much more highly heated than the second half thereof. The part of the stocking on the more highly heated part, therefore, dries more rapidly and there is then risk of the part already dried being destroyed or damaged by the further supply of heat to the hottest point of the form.

30 One object of the present invention is to provide a form which is so constructed as to be uniformly heated without waste of heat and to effect the uniform drying of the stocking applied thereto.

35 A further object of the invention is to provide a form having a foot portion comprising a fixed heel section and a detachable toe section or cap, with efficient heating means 40 for said foot portion, whereby toe sections or caps of different lengths may be employed in connection with one and the same form body.

The invention is illustrated in the accompanying drawing, in which:

Figure 1 is a transverse section, on line I—I of Figure 2, through a pair of stocking forms and a heat supplying apparatus of one type constructed in accordance with my 50 invention.

Figure 2 is a vertical longitudinal section on the line II—II of Figure 1.

Fig. 3 is a longitudinal section through a stocking form on an enlarged scale.

Figure 4 is a section on the line IV—IV 55 of Figure 3.

Figure 5 is a top view of a detail.

Figures 6 and 7 are, respectively, sections on lines VI—VI and VII—VII of Figure 3.

The hollow molds or forms 1 may be made 60 with advantage of sheet iron, aluminum or copper, and are mounted upon a table or plate 2, which is carried on legs 3. The molds or forms may be arranged in transverse rows, of any number to a row. As shown in Figures 1 and 3, the hollow interior of the mold or form 1 is divided by two inner division walls 4 into a number of compartments or 65 passages 5, 6 and 7. The compartment 5 forms a central inflow passage between the two other compartments 6 and 7, which serve as outflow passages. The passages 5, 6 and 7 are in communication at their upper ends, at or about the point of juncture of the leg portion with the foot portion of the form, 70 as clearly shown in Figure 3. The heating fluid to be used may consist of steam, hot air or gases, as desired.

The form is made up of a body or leg portion and a foot portion, and this foot portion is preferably of sectional construction, and comprises a fixed half or heel section 8 and a removable toe section or cap 9. The passages 5, 6 and 7 terminate at their upper ends at the point of juncture of the leg portion and heel section of the foot portion of the form, which latter is closed at its outer end by a combined closure and heat transmitting member 10. The inner portion of this member is cup-shaped, or in the form 80 of a flattened receptacle 11, which is intensely heated by the heated fluid flowing from passage 5 to passages 6 and 7. The walls of this cup-shaped receptacle may be ribbed or corrugated to increase its heating area. The member 10 has an intermediate portion or a projecting portion 12, the portion 12 being brazed or otherwise suitably fixed to the part 8. The projecting portion 12 of the member 10 is designed to form a support over which 85 90 95 100

may be fitted the inner end of the removable cap 9, which cap 9 has arranged therein a combined supporting and conducting plate 14 of good conducting material which is received in the member 10 and serves as a holding element to retain the cap 9 stably in position, while it also serves to transmit heat to the cap from the intensely heated member 10. Provision is thus made for heating a foot portion of the form uniformly and to a suitable temperature, while providing a cap section which is readily removable so that interchangeable cap sections of different lengths may be employed, allowing one and the same mold to be used for drying and shaping stockings of different sizes. The section 9 may be provided with perforations for the circulation of air therethrough if desired, and which may be used or not according to conditions.

In the present instance an air heater is shown for supplying heated air for heating the forms. This air heater comprises the table or plate 2 having openings 16 and 17 therein, the openings 16 communicating with the passages 5 of the forms and the openings 17 with the passages 6 and 7 of the forms. Extending along the underside of the table or plate 2 are superposed air chambers 18 and 19, separated by a division wall 20, and which are in communication at one end through a passage 21 formed in said division wall. The upper or supply chamber 18 communicates through the openings 16 with the passages 5 of the forms and the lower or suction chamber 19 communicates through the openings 17 with the passages 6 and 7 of the forms. In the chamber 19 is placed an electrical resistance heater 22, which is preferably disposed beneath the opening 21. In the chamber 18 is placed a rotary fan 23 which is driven by a motor 24 and draws air heated by the heating resistance 22 and other air from the chamber 19 and forces the mixture of both kinds of air through the chamber 18 into and through the passages 5, 6 and 7 of the forms and thence back through the chamber 19 for re-heating and re-circulation. From this it is evident that the air supplied to the forms, deprived of a portion of its heat, passes back to the air heater and is re-heated, so that economy in the use of heat is ensured, since the heating apparatus is only to generate the equivalent of the amount of heat dissipated, so that the thermal losses are very small.

It will, of course, be understood that changes in the form, construction and arrangement of parts may be made, within the scope of the appended claims, without departing from the spirit or sacrificing any of the advantages of the invention.

Having thus described my invention, I claim:

65 1. A stocking drying form comprising a

hollow body portion adapted to receive a heating fluid, a removable toe portion having a supporting plate attached thereto, and a socket formed in said body portion adapted to receive said supporting plate, said socket comprising walls extending inwardly from the end of the body portion and closing said body portion, said walls being spaced from the walls of the body portion throughout, to provide a heating jacket surrounding said 75 socket, whereby the heating fluid may circulate around all sides of said socket.

2. A stocking drying form comprising a hollow body portion adapted to receive a heating fluid, a removable toe portion having a supporting plate attached thereto, and a socket formed in said body portion adapted to receive said supporting plate, said socket comprising corrugated walls extending inwardly from the end of the body portion and closing said body portion, said corrugated walls being spaced from the walls of the body portion throughout, to provide a heating jacket surrounding said socket, whereby the heating fluid may circulate around all sides 90 of said socket.

In testimony whereof I affix my signature.

BRUNO SIMONIDES.
